UNITED STATES PATENT OFFICE.

HARRY C. GOODRICH, OF CHICAGO, ILLINOIS.

GUIDING ATTACHMENT FOR SEWING-MACHINES.

SPECIFICATION forming part of Letters Patent No. 399,873, dated March 19, 1889.

Application filed April 26, 1887. Serial No. 236,239. (Model.)

To all whom it may concern:

Be it known that I, HARRY C. GOODRICH, residing at Chicago, in the county of Cook and State of Illinois, and a citizen of the United States, have invented a new and useful Improvement in Attachments for Sewing-Machines, of which the following is a specification, reference being had to the accompanying drawings, in which—

- 10 Figure 1 is a top or plan view showing a piping and band gage adjusted for a line of stitching away from the edge; Fig. 2, a similar view showing the gage adjusted for a line of stitching close to the edge; Fig. 3, a similar view showing another form of arranging the adjusting-lever; Fig. 4, a detail showing the piping and band gage; Fig. 5, a detail showing the separator-plate; Fig. 6, a top or plan view showing another form of arranging 20 the adjusting-lever; Fig. 7, a similar view showing another form of combining the adjusting-lever with the gage; Figs. 8 and 9, top or plan views showing the adjusting feature combined with the hemmer.

25 The objects of my invention are to improve the construction and operation of gages used for directing the line of movement of piping and bands which are to be sewed together with a strip of ruffling, to improve the location and operation of the means for adjusting guides or gages for the proper line of stitching; and to improve the arrangement of the gages or guides and their adjustment in relation to their work; and its nature consists 30 in the several parts and combinations of parts, hereinafter described, and pointed out in the claims as new.

In the drawings, A represents a plate of a size and diameter to correspond to the ordinary plate for covering the shuttle-race, for 40 which plate the plate A can be substituted in applying the attachment which it carries, and this plate A is provided with a notch or recess, a, for withdrawing the plate.

45 B is a separator-plate, made of thin steel or other suitable material and having in its end a slot, b, for the passage of the needle, and this plate has a continuation or extension, B', on one side of which is an ear, b', by means 50 of which and suitable rivets the separator-plate can be attached in position on the plate A.

C is a plate of sheet-brass or other suitable

material, and having a side extension, C', to extend over the plate A, or partly thereover, when the attachment is ready for use. This 55 plate C, as shown in Figs. 1 and 2, has a slot, c, near its edge, through which the stem of a pin or rivet, c', can pass, the end of the stem or rivet being set or secured in the end of the extension B', as shown in Fig. 5, by which 60 means the plate C is connected so that it is free to move sidewise to the limit of the slot c. As shown in Fig. 3, the extension C' of the plate C does not extend the full width of the plate A, and at its terminal edge a tongue 65 or ear, c'', is turned, and, as shown in Fig. 6, a plate corresponding to that of Fig. 3 is represented, except that the ear c'', instead of being struck down, is struck up. As shown in Fig. 7, the extension C' has a continuation 70 parallel with the plate, and this continuation is connected with the plate A by a suitable pin or rivet, c'', which forms the pivot on which the plate C can be swung.

D is a lever which, as shown in Figs. 1 and 2, is pivoted to the plate A by a suitable pin, d, and is connected with the extension C' by a suitable pin, d', and the free end of the lever has a lip, d'', which engages with notches in the edge of a strip, d³, struck up from the 80 plate A at the edge of the opening a. The connection of the lever D with the plate C enables the plate C to be moved sidewise at its acting end to bring the gages which it carries in proper relation with the slot b in 85 the gathering-plate for the line of stitching, and the lip d'', in connection with the notches in d³, enables the lever to be maintained in whatever position it may be changed for adjustment of the plate C. As shown in Fig. 3, 90 the lever D, instead of being on top of the plate, as in Figs. 1 and 2, is located beneath the plate, and the connection between the lever and the extension C' is made by the turned-down ear c'', which enters a hole therefor in the lever D. This lever is pivoted at its forward end to the plate by a pin, d, and is provided at its free end with the lip d'' to engage with notches in the edge of d³, the same as for the construction described for 95 Figs. 1 and 2. As shown in Fig. 6, the lever D is pivoted so as to be in a reverse position from that shown in Fig. 1, and is located on top of the plate A, and the connection with

the extension C' is made by the turned-up ear c'', which enters a hole in the lever, and with this arrangement of lever the plate A has a turned-up portion, d³, at its forward 5 end, with notches thereon to be engaged by the lip d'' in the lever. As shown in Fig. 7, the lever D is located on top of the plate, and is pivotally connected with the plate by a pin, d, and instead of the lip and notches for locking 10 the lever in its position a turned-over lip, d⁴, secured to the plate A, is employed for engaging the body of the lever D and holding the lever by frictional contact, and the connection of the lever D with the extension C' is, by means of lugs or projections c⁴ on the extension, located each side of the lever and in engagement with the edges of the lever. 15

The several forms shown for connecting the lever D with the plate C and the several 20 forms of the plate and location of the lever all attain the same end of furnishing the means for adjusting the acting end of the plate in proper relation for the stitching, and to this end various other modifications could 25 be used.

E is the guide or gage for the band or garment to which the ruffled strip and the piping are to be sewed. This guide or gage is formed of a strip struck from the plate C and turned 30 on itself to form a tongue, e, leaving an opening, e', between the tongue and the portion of the strip running out from the plate C, and the end of the tongue e is rounded, and an opening, e'', left between this rounded 35 end and the straight edge g of the plate C. The garment or band which is operated upon by this guide or gage E is folded on itself at the edge and is then slipped into place to have the body or main portion of the garment or band below the guide or gage E, as a 40 whole, and the folded edge lie over the end of the tongue e and pass beneath the body of the guide, which extends out from the plate C, so that the tongue e will lie between the 45 body of the garment or band and the fold thereof, and the folded edge of the garment or band will lie between the end of the tongue e and the edge g of the plate C, and this manner of inserting the garment or band in connection with the end of the tongue e and the 50 guiding-edge g maintains a straight line of travel, as the fold is held between the end of e and the edge g.

F is a guide or gage for the piping. This 55 guide or gage F is formed from a strip struck from the plate C and bent on itself to form a tongue, f, with an opening, f', between the tongue F and the body or portion running out from the plate, and the end of the tongue is 60 rounded, and between this rounded end of the tongue and the edge h of the plate C is an opening, f''. The piping is formed of a narrow strip of material folded centrally, and this narrow strip is inserted by placing it in 65 position to have the end of the tongue lie between the fold with the fold in the opening between the rounded end and the straight

edge h, so that one side of the fold will be above and the other below the tongue and both sides of the fold pass beneath the portion of the guide connected with the plate C. The straight edge h is deeper than the edge g, by means of which the edge of the piping projects slightly beyond the edge of the band or garment, leaving a line of separation formed by this projecting edge of the piping between the edge of the band or garment and the ruffle, it being understood that the strip to be ruffled lies wholly beneath the plate C and above the separator-plate B, 75 as is usual in forming ruffles. The rear end of the plate C is provided with a guide, and, as shown in Figs. 1 and 2, this guide is formed by a strip, i, thrown up to lie in a plane above the plane of the plate C, and in front of this 80 piece i is an opening, i', having a straight edge, j, against which edge the material being operated upon is guided, the material passing under the lip i and its insertion to lie against the edge j being permitted by the 85 opening i'. A similar guide is provided in the construction shown in Fig. 7. As shown in Figs. 3 and 4, a lip, i, is formed by striking a strip down from the plate C and turning in 90 on itself, so as to leave an edge, j, for guiding the material. The plate C, in the construction shown in Figs. 1 and 2, is held and guided at its front or forward end by a guide-lip struck down and under, so as to clasp or encircle or lie beneath the plate B, and, as 95 shown in Figs. 3 and 6, the plate is guided and held by cutting a slot in its edge and a corresponding slot in the extension B' of the plate B, and turning lips or ears l on both 100 edges of the slot in C around and beneath the plate-extension B'. 105

The adjustable feature by means of the lever D can be applied to and used with other attachments than the combined band and piping gage—as, for instance, with a hemmer; and such construction is shown in Fig. 8, in which G represents a hemmer formed on or attached to the plate H, having an extension, H', the plate H having a slot and being held in place by a pin similar to the construction shown in Fig. 1 for the plate C, except that the attaching-pin is under the plate A. The lever D in this arrangement is pivoted at d to the plate A and connected by a pin, d', to the extension H', and the lever is held in its adjustment by a lip, d'', and notches in the edge of the projection d³. As shown in Fig. 9, the extension H' of the plate H is carried around so as to form a lever to take the place of the lever D, and in this construction the plate H is movable sidewise, as the pivot is inserted in a hole of corresponding diameter in the plate H, leaving the plate free to swing on its pivot, and the extension H' is locked to the plate A by a suitable pin and 120 notches corresponding to d'' and d³. 125

The operation of the band and piping gage or guide is as follows: The strip for the ruffle is placed beneath the plate C above the sep-

arator B. The piping-strip is folded and placed over the tongue *f* and beneath the body portion of the guide F, as already described—in other words, it lies upon the strip 5 to be ruffled. The garment or band to which the ruffle and piping are to be sewed is folded over at its edge and inserted in the guide E, as already described, and the piping-strip and band or garment at the folded edge is inserted 10 beneath the lip *i*, so as to lie against the guiding-edge *j*. The device is now ready for use, and when in use the several pieces are carried forward by the feed of the machine, as usual, and it will be seen that the piping-strip 15 is guided and held in its proper relation by the guide or gage F, and at the same time the garment or band is guided and held in its position by the guide or gage E, and as both of these guides have a bearing on the material 20 with which they can act on each side of the fold, by reason of the ends of the tongues and the guiding-edges *g* *h*, the material cannot move otherwise than in a straight line, and this without any assistance from the 25 hand of the operator, as the material is held against movement in both directions through the guiding-edges and the guiding-points. The guiding-edge *j* assists in maintaining a straight line of travel, as it holds the material 30 from turning against the feed, as might happen in case the three pieces to be sewed together were moving, so that the feed would not properly act owing to the thickness of the material.

35 The combined guide or gage can be adjusted to bring the line of stitching in proper relation to the edge of the material by adjusting the guides or gages E F to or from the needle, as may be required, by means of the 40 adjusting-lever D, the moving of the acting end of the plate C away from the needle bringing the line of stitching farther from the edges of the piping and band, and the movement of such end in the opposite direc-

tion bringing the line of stitching nearer 45 the edge, and this adjustment will be found valuable, for the reason that the descent of the needle is not always in line with the center of the needle-hole, and by moving the plate C the edge of the piping and the band 50 can be brought in the exact relation required for the center of the needle. This feature of adjustment and attachment to bring the line of stitching in line with the center of the needle and in proper relation to the edge of 55 the material will be found beneficial for various sewing-machine attachments other than the combined guide or gage, and its use in connection with a hemmer is illustrated in Figs. 8 and 9, and in this connection the delivering end of the hemmer can be adjusted for centering the stitching in relation with the edge by moving it to or from the needle through the lever D in the manner already described for the combined guide or gage. 60

What I claim as new, and desire to secure by Letters Patent, is—

1. The combination, with the separator-blade B, of the plate C, adjustable with relation to said separator-blade and carrying guides E 70 and F, having backwardly-turned tongues *e* and *f*, respectively, said guides being provided with openings *e'* *e''* and *f'* *f''*, respectively, and the plate C being provided with straight edges *g* and *h* opposite said guide-openings, 75 substantially as described.

2. The combination, with the plate A and the separator-plate B, of the adjustable plate C, carrying guides E, F, and *i*, and the lever D, pivoted to the plate A and connected with 80 the plate C, for the purpose of adjusting said plate C to bring the material acted upon into proper relation with the line of stitching, substantially as described.

HARRY C. GOODRICH.
